UNITED STATES PATENT OFFICE.

SETH A. CRONE, OF NEW YORK, N. Y.

BRAKE-HEAD FOR RAILWAY-CAR BRAKE-BEAMS.

SPECIFICATION forming part of Letters Patent No. 740,092, dated September 29, 1903.

Application filed July 6, 1903. Serial No. 164,307. (No model.)

To all whom it may concern:

Be it known that I, SETH A. CRONE, a citizen of the United States, and a resident of New York, in the county of New York and State 5 of New York, have invented certain new and useful Improvements in Brake - Heads for Railway-Car Brake-Beams, of which the following is a specification.

The invention relates to improvements in 10 brake-heads for railway-car brake-beams; and it consists in the novel features and combinations of parts hereinafter described, and particularly pointed out in the claims.

Brake-beams of the class to which my invention 15 pertains comprise a body-beam of suitable length, brake - heads on the ends thereof adapted to receive the brake-shoes, and a fulcrum or strut for the brake - lever, one division of brake-beams employing a ful- 20 crum and the other or trussed beams comprising a strut; and my invention has for its object to produce a novel brake - head for the ends of the body-beam whether the latter be a structural beam or a flanged beam, the said 25 brake - head being efficient and capable of being firmly and quickly applied to the ends of the beam and of receiving and firmly holding the brake-shoes.

The brake-head of my invention is formed 30 from a blank or blanks of forged metal bent to the required shape and adapted to be secured upon the end of the body-beam and to effectually receive and support the brake- shoe.

35 The purpose of my invention is to materially improve brake-shoe heads and to produce a brake - shoe head capable of withstanding the severe uses to which brake-shoe heads are put and which shall be efficient and durable 40 and not likely at any time to become fractured or broken.

The invention will be fully understood from the detailed description hereinafter presented, reference being had to the accompanying 45 drawings, in which—

Figure 1 is a side view of a brake-shoe head and brake - shoe constructed in accordance with and embodying my invention, the said head being shown as applied to an ordinary 50 flanged body-beam, the latter being in section. Fig. 2 is a detached side elevation of the brake - head. Fig. 3 is an end view of

same looking in the direction of the arrow in Fig. 2. Fig. 4 is a horizontal section of a portion of same on the dotted line 4-4 of Fig. 2. 55 Fig. 5 is a detached plan view of a blank employed in the formation of a part of one desirable construction of the brake-head. Fig. 6 is a view, partly shaped, of the blank from which the brake-head shown in Figs. 1 and 2 60 is formed; and Fig. 7 is an edge view of same.

In the drawings, 10 designates a customary form of brake-shoe, 11 a customary form of body-beam, and 12 the brake-head of my invention, this head being of forged metal and 65 having the shoe 10 secured to it by means of the pin 13, which is of usual form and construction.

The brake-head may be described as comprising an inner face portion 14 to receive 70 the shoe 10 and an outer face or portion 15 to be applied to the body-beam 11. The inner face or portion of the brake-head is at its ends formed with the bearing-surfaces 16 for contact with the end surfaces of the brake- 75 shoe 10 and at its central portion with the bearing-surface 17 for contact with the inner end of the central lug 18 on said brake-shoe, while at the opposite ends of the said bearing- surface 17 the said head is formed with 80 the projecting pockets 19, which lie at the upper and lower ends of the said lug 18 and at their upper and lower ends are open in line with the usual opening in the lug 18, so that the pin 13 may pass through said pockets 85 19 and lug 18, as shown in Fig. 1, for the purpose of detachably fastening the shoe 10 to the brake - head. The pockets 19 are formed by slitting the metal blank on the lines 20 20, Fig. 6, and depressing the metal 90 of the blank intermediate said lines, so that said metal thus depressed shall constitute a pocket or loop, this pocket or loop having a closed outer end where it contacts with the shoe and closed sides, but open at its upper 95 and lower ends, so as to form a passage for the pin 13. The pockets or loops 19 19 correspond exactly with each other, and their primary purpose is to afford projections to contact with the inner face of the shoe 10 and to pass into line with the upper and 100 lower ends of the lug 18 of said shoe, so that the pin 13 may be applied for securing the shoe 10 in position. In the preferred con-

struction of the head I also make use of the loops or pockets 19 and pin 13 as a means for aiding in securing the head and shoe to the body-beam 11, and in carrying out this feature of the construction, which is shown in Fig. 1, I first provide a blank 21, (shown in Fig. 5,) having projecting end lips 22 and slits 23, these slits 23 substantially corresponding with the slits formed on the lines 20 preliminary to the formation of the loops or pockets 19. The blank 21 when prepared as shown in Fig. 5 then has the metal intermediate the slits 23 depressed into the form of loops 24, corresponding with but 15 smaller than the loops or pockets 19 of the head, and the said loops 24 of the plate or blank 21 are then inserted into the said loops or pockets 19, as shown in Fig. 1, so that they may not only strengthen the said loops or 20 pockets 19, but afford a means for securing the plate 21 against the rear side of the front 14 of the brake-head, said plate when so applied to the head leaving the lips 22 projecting outwardly in position to be turned over 25 upon the flange of the beam 11, whereby to aid in securing the head to said beam and in rendering the entire structure more rigid and durable. When the loops 24 of the plate 21 are inserted within the loops or pockets 19 of 30 the brake-head, a double thickness of metal is provided intermediate the pin 13 and the shoe 10 and also at the opposite edges of said pin, which when in position will lock the plate 21 in its location and enable said plate 35 through its lips 22 to effectually bind against the flange of the beam 11.

The front 14 of the brake-head is about on 40 central lines traversing the pockets or loops 19 formed with shoulders 25, against which the end edges 26 of the plate or blank 21 may contact, said shoulders 25 forming in effect a recess to receive the body of the plate or blank 21 and aid in securing the latter firmly in position. In instances in which it may be desired not to employ the plate 21 the recess 45 formed by the shoulders 25 would directly receive the flange of the body-beam 10 and aid in centering the brake-head upon said flange.

From the lower edge of the lower loop or 50 pocket 19 of the brake-head the front face thereof curves downwardly and outwardly to the bearing-surface 16, at the lower end of which the plate or blank from which the head is formed is turned upwardly upon itself to 55 form one section of the outer face portion 15 of said head, the two portions contacting with each other below the lower loop or pocket 19 and being bound together in the preferred construction by a tongue 27, formed from the 60 metal of the blank and pressed outwardly therefrom and upwardly against the said outer portion 15 of the said brake-head. The lower section of the outer portion of the brake-head passes upwardly to the web of the beam 11, 65 where it is formed into a flange 28, adapted to be secured to said web and conforming to a flange 29, formed on the upper section of

the outer portion 15 of said head. From about the upper edge of the upper loop or pocket 19 the inner face 14 of the head is 70 curved inwardly to form the loop 30 and then upwardly and out to the upper bearing-surface 16 for the shoe 10, at the upper edge of which surface 16 the metal of the blank or plate is folded over upon itself and carried 75 downwardly to engage the outer surface of the loop 30 and also to pass into engagement with the web of the beam 10, this portion of the blank being formed integrally with the flange 29, through which and the flange 28 80 the rivet 31, for securing the head upon the beam, may pass.

At the upper end of the brake-head is formed the eye 32, to which in the usual manner the suspending-chains may be attached, and this 85 eye 32 is, like the tongue 27, formed from the metal of the blank out of which the entire brake-head is formed. In the formation of the eye 32 and tongue 27 I slit the metal blank on the lines 33 33 for the eye 32 and on the 90 lines 34 for the tongue 27 and then in forming the blank into a finished head press outwardly those portions of the metal between the slits 33 and between the slits 34 to form, respectively, the eye 32 and tongue 27. 95

The entire brake-head is when the plate 21 is not employed formed from one strip or blank of forged metal first bent into the preliminary outline shown in Figs. 6 and 7 and then into the finished condition shown in 100 Figs. 1 and 2. When the plate 21 is made use of, the entire brake-head is then formed of but two pieces of forged metal, and in either construction the main body of the head is in one integral piece of forged metal so 105 shaped that it may effectually resist the strains likely to come upon it and to efficiently and properly receive, support, and maintain the shoe 10.

At the upper end of the head the metal of 110 the blank may be stiffened and strengthened, if desired, by, while cutting the slits 33, pressing the metal at the outer sides thereof outwardly to the position indicated by the dotted lines 35 and then pressing the outer 115 edges of this portion of the metal outwardly to form angle-iron flanges, which will appear in the finished head at the upper end of the latter and at the opposite sides of the eye 32. 120

The outer portion 15 of the head above described is shown as applied to a flanged beam 11; but in the construction of trussed beams the body-beam is in the form of a channel or other structural shape, and when my brake-head is to be applied to this character of body-beams the ends of the blank instead of being brought together to form the flanges 125 28 29 to engage the web of a flanged beam will be conformed to the upper and lower surfaces of the channel or other structural beam without, however, other modifications in the general body of the forged-metal head. 130

I prefer to form the loops or pockets 19 and 24 in the manner hereinbefore described, so

that they shall have closed outer ends and closed vertical sides and be open at their upper and lower portions, and such formation of said pockets constitutes a part of my invention; but I desire it understood that I do not in every instance confine the other novel features of my invention to any special manner of forming the pockets to receive the pin 13. What I claim as my invention, and desire 10 to secure by Letters Patent, is—

1. The brake-shoe head having the arched inner face portion to engage the brake-shoe and the outer portion to engage the beam and both of said portions being formed from one integral blank of forged metal bent to shape, said inner face portion having the integral loops 19 pressed from said blank to engage the brake-shoe and receive the brake-shoe pin, said loops 19 having the closed outer 15 end and closed vertical sides and being open at their upper and lower portions for the passage of said pin; substantially as set forth.
2. A brake-shoe head comprising the face portion of forged metal pressed to shape, said portion being equipped with outwardly-projecting loops 19, combined with the brake-shoe having the apertured lug interposed between said loops, and the pin adapted to be passed through said loops and lug for securing 20 said head and shoe together, said loops 19 having the closed outer end and closed vertical sides and being open at their upper and lower portions for the passage of said pin; substantially as set forth.
3. The brake-shoe head having an inner face portion to engage the brake-shoe and an outer portion to engage the beam and both of said portions being formed of forged metal, said inner portion having the loops 19 and 25 bearing-surfaces 16 and being arched inwardly, and said outer portion at its outer upper section having the integral eye 32 formed from the metal of the blank for said head; substantially as set forth.
4. The brake-shoe head having an inner face portion to engage the brake-shoe and an outer portion to engage the beam and both of said portions being formed of forged metal, said inner portion having the loops 19 and 30 bearing-surfaces 16 and being arched inwardly, and said outer portion at its upper section having the integral eye 32 formed from the face and outer portions of the head, said portions having the slits 33 the metal 35 between which is bent upwardly to form said eye; substantially as set forth.
5. The brake-shoe head having an inner face portion to engage the brake-shoe and an outer portion to engage the beam and both of said portions being formed of forged metal, said inner portion having the loops 19 and bearing-surfaces 16 and being arched inwardly and said outer portion at its lower section having the integral securing-tongue 40 27 formed from the metal of the blank of said head; substantially as set forth.
6. The brake-shoe head having an inner

face portion to engage the brake-shoe and an outer portion to engage the beam and both of said portions being formed of forged metal, 7 said inner portion having the loops 19 and bearing-surfaces 16 and being arched inwardly, and said outer portion at its lower section having the integral securing-tongue 27 formed from the face and outer portions 7 of the head, said portions having the slits 34 the metal between which is bent outwardly and upwardly against said outer portion to bind said portions together; substantially as set forth.

7. A brake-shoe head comprising the face portion of forged metal pressed to shape, said portion having the end bearing-surfaces 16 and the integral outwardly-projecting loops 19, combined with the brake-shoe at its ends 8 in engagement with said bearing-surfaces 16 and having the apertured lug 18 interposed between said loops, and the pin adapted to be passed through the ends of said head, said loops and said lug for securing said head and shoe together, said loops 19 having the closed outer end and closed vertical sides and being open at their upper and lower portions for the passage of said pin; substantially as set forth.

8. The brake-shoe head having the arched inner face portion to engage the brake-shoe and the outer portion to engage the beam and both of said portions being formed from one integral blank of forged metal bent to shape, said 100 inner face portion having the integral loops 19 pressed from said blank to engage the brake-shoe and receive the brake-shoe pin, combined with the plate 21 having the loops 24 to engage the loops of the head proper and 105 the end lips 22 to engage the beam; substantially as set forth.

9. The brake-shoe head having the arched inner face portion to engage the brake-shoe and the outer portion to engage the beam and 110 both of said portions being formed of forged metal, combined with an inner plate 21 having loops 24 projected through openings in said inner face portion to receive the brake-shoe key-pin; substantially as set forth.

10. The brake-shoe head having the arched inner face portion to engage the brake-shoe and the outer portion to engage the beam and both of said portions being formed of forged metal, combined with an inner plate 21 having loops 24 projected through openings in 115 said inner face portion to receive the brake-shoe key-pin, and also having lips 22 to engage the beam; substantially as set forth.

11. A brake-shoe head comprising the face 125 portion of forged metal pressed to shape, said portion having end bearing-surfaces 16, projecting loops 19 and inwardly-projected loop 30, said loops 19 having the closed outer end and closed vertical sides and being open at 130 their upper and lower portions; substantially as set forth.

12. The brake-shoe head having the arched inner face portion to engage the shoe and the

outer portion to engage the beam and both of said portions being formed from a blank of forged metal pressed to shape, said inner face portion having at its rear face the shoulders 25 forming between them the recess; substantially as set forth.

13. The brake-shoe head having the arched inner face portion to engage the shoe and the outer portion to engage the beam and both of 10 said portions being formed from a blank of forged metal pressed to shape, and means for securing said inner face portion and said outer portion together; substantially as set forth.

14. A brake-shoe head comprising the inner 15 face portion of forged metal pressed to shape, said portion being equipped on one side with loops 19 and on its other side with the shoulders 25 forming between them a recess; substantially as set forth.

15. A brake-shoe head comprising the face portion of forged metal pressed to shape and having the integral loops 19 projected therefrom, said loops 19 having the closed outer

end and closed vertical sides and being open at their upper and lower portions; substantially as set forth. 25

16. A brake-shoe head comprising the face portion of forged metal pressed to shape, and a plate 21 applied thereto, said plate 21 having the integral loops 24 projected therefrom 30 and said loops being open at their upper and lower portions; substantially as set forth.

17. A brake-shoe head comprising the face portion of forged metal pressed to shape, and a plate 21 applied thereto, said plate 21 having the end lips 22 and loops 24, the latter being open at their upper and lower portions; substantially as set forth. 35

Signed at New York, in the county of New York and State of New York, this 2d day of July, A. D. 1903. 40
